COMBINED SIGNAL LIGHT AND YARN HOLDER

Irving Kasher, 57 Water St., Perth Amboy, N.J.

Filed Apr. 30, 1965, Ser. No. 85,037

Term of patent 14 years

(Cl. D72—1)

FIG. 1.

FIGURE 1 is a front elevational view of the combined signal light and yarn holder, showing my new design;

FIGURE 2 is a side elevational view thereof; and

FIGURE 3 is a top plan view thereof.

The dominant features of my design reside in the portions shown in full lines, it being understood that the electric cord is omitted from FIGURE 3 for convenience of illustration.

I claim:

The ornamental design for a combined signal light and yarn holder, as shown and described.
